UNITED STATES PATENT OFFICE.

LUCIUS H. CURTIS, OF SALT LAKE CITY, UTAH.

STOVE OR FURNACE.

SPECIFICATION forming part of Letters Patent No. 681,444, dated August 27, 1901.

Application filed February 8, 1901. Serial No. 46,565. (No model.)

To all whom it may concern:

Be it known that I, LUCIUS H. CURTIS, of Salt Lake City, in the county of Salt Lake and State of Utah, have invented certain new and useful Improvements in Stoves or Furnaces; and I do hereby declare the following to be a full, clear, and exact description of the invention, such as will enable others skilled in the art to which it appertains to make and use the same.

My invention relates to an improvement in stoves and furnaces, and more particularly to an improved means for preventing the accumulation of gas and the explosions incident thereto in the fire-box, the object of the invention being to provide a series of detachable or permanent pipes in the fire-box connecting the ash-pit and fire-box in such manner as to permit the air from below the grate to pass up to the top of the fuel and supply the necessary oxygen to consume all gas.

With this object in view the invention consists in certain novel features of construction and combinations and arrangements of parts, as will be more fully hereinafter described, and pointed out in the claims.

In the accompanying drawings, Figure 1 is a view in section illustrating my improvements, and Figs. 2, 3, 4, and 5 are views illustrating modified forms of my invention.

1 represents a stove provided with an ordinary grate 2, dividing the stove into the fire-box or combustion-chamber 3 and the ash-pit 4.

35 In the drawings I have illustrated my improvements in connection with an ordinary heating-stove, but would have it understood that the improvements are equally applicable for use in cooking-stoves, furnaces, or any 40 form of stove employing a fire-box and an ash-pit below the same.

My improvements consist of a series of vertical pipes 5, secured around the interior of the fire-box and resting on the grate, so as to 45 permit the air from below the grate to pass up through the pipes and be discharged in a highly-heated condition at the top of the fuel to consume the gas which would otherwise collect and cause explosions or escape without being burned, thus resulting in a waste of 50 heat which the fuel should give and which

will be utilized when my improvements are employed. The pipes 5 may be slotted in one side for the reception of headed bolts 6, which latter are passed through the fire-lining and 55 stove-body and secured in place by nuts 7, or they may be removably secured in the fire-box by any other means or may be placed loosely in the box or made integral with the fire-lining, as shown in Fig. 2. The pipes 5 60 may be perforated throughout their length to discharge into the fuel, as shown in Fig. 3.

Instead of making the pipes 5 round or cylindrical I might make the same rectangular, as shown in Fig. 4; or I might employ a series 65 of solid rods 8, having roughened peripheries, as shown in Fig. 5. These rods 8 are arranged around the fire-box, and the roughened peripheries of the rods will insure a space all around them for the passage of the air up 70 from the ash-pit into the fire-box.

If desired, a circular perforated pipe may communicate with the upper ends of the vertical pipes 5 and extend all around the fire-box to distribute the air to the gas formed 75 therein. Various other slight changes might be resorted to in the general form and arrangement of the several parts described without departing from the spirit and scope of my invention, and hence I would have it 80 understood that I do not limit myself to the precise details set forth, but consider myself at liberty to make such slight changes and alterations as fairly fall within the spirit and scope of my invention.

Having fully described my invention, what I claim as new, and desire to secure by Letters Patent, is—

1. In a stove or furnace, the combination with the fire-chamber and the ash-pit, of a 90 series of removable devices located inside and constituting a lining for the fire-chamber, means for removably securing said devices in place in said chamber, said devices constructed and adapted to permit the passage of air from the ash-pit, around the fuel 95 in the fire-chamber and above said fuel.

2. The combination with the fire-chamber and ash-pit of a stove or furnace, of a series of independent tubes located within and constituting a lining for the fire chamber, means for removably securing said tubes in place,

each of said tubes in open communication at its lower end with the ash-pit and in open communication at the other end with the fire-chamber above the fuel-space.

- 5 3. The combination with the fire-chamber and ash-pit of a stove or furnace, of a series of tubes located inside the fire-chamber and communicating at one end with the ash-pit and at the other end with the fire-chamber
10 above the fuel-space, and removable fasten-

ing devices securing said tubes to the inner wall or face of the fire-chamber.

In testimony whereof I have signed this specification in the presence of two subscribing witnesses.

LUCIUS H. CURTIS.
